CLAIM

We claim the ornamental design for a penis phototherapy device, as shown and described.

DESCRIPTION

FIG. 1 is a bottom, front, left perspective view of a penis phototherapy device, showing our new design;

FIG. 2 is a top, front, right perspective view thereof;

FIG. 3 is a bottom, rear, left perspective view thereof;

FIG. 4 is a bottom, rear, right perspective view thereof;

FIG. 5 is a front elevation view thereof;

FIG. 6 is a back elevation thereof;

FIG. 7 is a right-side elevation view thereof, the left-side elevation view being a mirror image thereof;

FIG. 8 is a top plan view thereof; and,

FIG. 9 is a bottom plan view thereof.

In the drawings, the equal-length broken lines depict portions of the penis phototherapy device that form no part of the claimed design.
